UNITED STATES PATENT OFFICE.

ERNST RUETTGERS, OF BROOKLYN, NEW YORK.

NAIL-FILE OR SIMILAR INSTRUMENT.

No. 901,743.

Specification of Letters Patent.

Patented Oct. 20, 1908.

Application filed December 19, 1907. Serial No. 407,110.

To all whom it may concern:

Be it known that I, ERNST RUETTGERS, a citizen of the United States of America, and a resident of Brooklyn, county of Kings, and State of New York, have invented certain new and useful Improvements in Nail-Files or Similar Instruments, of which the following is a specification, reference being had to the accompanying drawings, forming a part 10 thereof.

My invention relates to improvements in nail files and similar instruments, and particularly to a new form and construction of handles therefor. The handle comprises 15 two sheets of flexible material arranged one on either side of the tang of the instrument, said sheets being preferably of a greater width than the said tang, and a binding strip U-shaped in cross section which surrounds 20 and tightly engages the said sheets. The tang is preferably of a width less than the width of the sheets and is also preferably provided with a recess along one edge thereof, the sheets being provided with a corresponding recess, whereby upon engaging the binding strip tightly around the edges of the sheets the sheets will be pinched together over the edges of the tang in such a manner 25 as to retain the parts very tightly in position. The object of my invention is to construct 30 a simple and inexpensive form of handle for instruments of this character and one which will be securely held in position so that it will not be liable to accidental displacement, and further one which will readily lend itself to 35 inexpensive decoration, or, if preferred, the carrying of advertising matter.

In order that my invention may be fully understood I will now proceed to describe an 40 embodiment thereof, having reference to the accompanying drawings illustrating the same, and will then point out the novel features in claims.

In the drawings: Figure 1 is a face view of 45 a nail file provided with a handle constituting an embodiment of my invention. Fig. 2 is an edge view of the same. Figs. 3 and 4 are transverse sectional views upon the plane of the line 4—4 of Fig. 1 showing the handle as 50 in the process of construction and as completed respectively. Fig. 5 is a detail view showing a portion of the file and the handle therefor in central longitudinal section.

While I have illustrated my invention in 55 connection with a nail file, it will be understood that such is but one of many adapta-

tions of the same, and that in so describing and illustrating the invention I by no means wish to be limited to such use.

The nail file illustrated comprises the main 60 or body file portion 6, and a tang 7. The tang is of considerably less width than the main or body portion and is further provided with a recess 8 along one edge thereof, as is clearly shown in Fig. 5. Two sheets of 65 flexible material 9—9 are disposed upon either side of the said tang, the width of the said sheets being greater than the width of the tang, such width in the present instance, being substantially the width of the body 70 portion of the instrument at a point contiguous to the handle. These sheets are also provided with recesses 10 corresponding with, and arranged opposite to, the recess 8 of the tang 7. A binding strip 11 surrounds the 75 edges of the sheets 9, following the contour thereof, as will be readily understood by reference to the drawings. This binding strip when first put in place is sufficiently open to readily receive the edges of the strips, 80 as is shown in Fig. 3; but after being thus placed in position it is stamped down so as to tightly engage the edges of the sheets and to pinch them together beyond the edges of the tang, as clearly appears in Fig. 4. The result of this is to hold the parts very tightly 85 in position, this effect being enhanced by the recessed portion of the tang 8 and the corresponding recesses 10 in the edges of the sheets 9. In fact, when such recess is employed the locking effect is so great as to 90 make it almost impossible to withdraw the handle except by breaking or straining some part of it.

The sheets 9 may be of any suitable material. They may be thin sheet metal, if desired, or may be of some such material as celluloid. It will be seen that sheets of this form readily lend themselves to inexpensive 95 decoration, because such decoration may readily be stamped therein while in the sheet form. Advertisements, furthermore, may be readily impressed upon the sheets in this manner if desired, or if such material as celluloid be employed advertisements may 100 readily be printed thereon. For the more expensive instruments, I may use a precious metal for the side plates, if preferred, and similarly the binding strip 11 may be of any 105 suitable metal as may be desired.

What I claim is:

1. A handle for a nail file or similar instru-

ment having a tang comprising two sheets of flexible material arranged one upon either side of the tang, and a binding strip U-shaped in cross section surrounding and tightly engaging the edges of the said sheets.

2. A handle for a nail file or similar instrument having a tang comprising two sheets of flexible material arranged one upon either side of the tang, said sheets being of greater width than the said tang, and a binding strip U-shaped in cross section surrounding and tightly engaging the edges of the said sheets, whereby the edges of the said sheets are pinched together beyond the edges of the said tang.

3. A handle for a nail file or similar instrument having a tang with a lateral recess comprising two sheets of flexible material arranged one upon either side of the tang, said sheets having a recessed portion along one edge thereof co-incident with the recess in

the tang, and a binding strip U-shaped in cross section surrounding and tightly engaging the edges of the said sheets.

4. The combination with a nail file or similar instrument provided with a tang having a lateral recess, of a handle therefor comprising two sheets of flexible material arranged one on either side of the said tang, said sheets being of a width greater than the width of the said tang, and having a recess along one edge thereof co-incident with the recess in the said tang, and a binding strip U-shaped in cross section surrounding and tightly engaging the edges of the said sheets, whereby they will be pinched together beyond the edges of the said tang.

ERNST RUETTGERS.
